UNITED STATES PATENT OFFICE.

WILLIAM O. RENKIN, OF ORADELL, NEW JERSEY, ASSIGNOR TO QUIGLEY FURNACE SPECIALTIES CO., INC., A CORPORATION OF NEW YORK.

YIELDING SUPPORTING AND VERTICALLY-GUIDING APPARATUS.

1,308,370.

Specification of Letters Patent.

Patented July 1, 1919.

Original application filed July 29, 1918, Serial No. 247,268. Divided and this application filed November 22, 1918. Serial No. 263,693.

To all whom it may concern:

Be it known that I, WILLIAM O. RENKIN, a citizen of the United States of America, residing at Oradell, county of Bergen, State 5 of New Jersey, have invented certain new and useful Improvements in Yielding Supporting and Vertically-Guiding Apparatus, of which the following is a specification.

My invention relates to apparatus for 10 yieldingly supporting bodies, such as bins for containing powdered or granular material which can be caused to flow into and out of said bins. It is particularly designed for use in cases where the vertical movements of the bin on its yielding supports are employed to automatically control the flow of the said materials.

My present application is a division of my prior allowed application Serial No. 20 247,268, filed July 29, 1918, and shows the invention as embodied in an apparatus for handling and storing powdered coal. In the accompanying sheet of drawings,

Figure 1 is a side elevation of a branch 25 or local storage bin for powdered coal with my invention applied thereto.

Fig. 2 is an enlarged detail of one of the supporting cams and coöperating parts, some of which are broken away or shown 30 in section.

Fig. 3 is a similarly enlarged detail view taken at right angles to the plane of Fig. 2.

Throughout the drawings like reference characters indicate like parts.

35 10, represents a closed bin for receiving and storing a supply of powdered coal for neighboring furnaces until such fuel is fed to the combustion chambers by controllers 6, 6, which deliver regulated quantities of 40 the material in the storage bins to the furnaces served by them. Said controllers are preferably of the construction shown in my pending application Serial No. 204,788, filed November 30, 1917, and are driven through 45 the belt and pulley and countershaft systems 8, 8, or other suitable driving apparatus, from electric motors 7, 7, supported from the bins.

The coal is delivered through pipe 12, to 50 cyclone separator 9, rigidly supported on framework 39, above bin 10.

According to my present invention the various storage bins are mounted upon yielding supports so that each bin rises or falls

slightly as the weight of its contents varies. 55 This vertical motion of the bin I utilize to operate an air valve which controls the supply of compressed air to a pneumatic motor device which operates the switch valve controlling the supply to that particular 60 bin. These elements are illustrated and described in the application Serial No. 247,268, filed July 29, 1918, (Case G) of which this is a division.

To enable the bin to rise and fall under 65 variations in the weight of its contents, I support the same preferably upon a sill frame 37, provided with vertical guides 38, by which the bin is compelled to rise and fall in a vertical line on the supporting 70 cams 41 and 42. These cams are fast on shafts 47 and 48, which are journaled on base frame 39. There are four of them for each bin, two on each shaft. The shafts 47, 48, have oppositely extending crank arms 75 43 and 44, which are connected by connecting rods 45, adjustable by means of turn-buckle 49. The cams have flanges 15 and 16, which overlap the sill 37, and thus prevent lateral movement of the bin. One or more 80 of the cams are supported by stiff compression springs 40, which are bedded at their lower ends in the supporting base frame 39, and at their upper ends have a flexible 85 connection 46, of the ball and socket type, with the under surfaces of the cam flanges. As the result of this construction the cams rotate synchronously under the control of 90 springs 40, and slightly raise or lower the bin as the variations in the weight of its 95 contents permit or compel the springs 40, to expand or contract. The bin is of course supplied with some kind of a flexible or telescoping connection to the conduit system and rigidly supported separator 9, as 100 indicated at 50.

The cams have flat surfaces 35, on which the flat surfaces of the under portions of sills 37, may rest when the bin is in its lowermost predetermined position, and other flat 100 surfaces 36, which strike against vertical guides 38, when the bin is in its highest predetermined position. These two features of construction serve as stops limiting the downward movement of the bin and the upward rotation of the cams.

In operation any increase in weight of bin 10, and its contents rotates cams 41 in a

clockwise direction against the partially yielding opposition of spring 40. Through connecting rods 45, an equal but opposite motion is transmitted to cams 42. If the bin should be overloaded, or one or more of the springs 40, should break, the sills 37, will then come down on flat portions 35, of the cams and further fall of the bin will then cease. If, on the other hand, the bin should rise above the predetermined limit of upward motion the other flat surfaces 36, of the cams will strike against guides 38, and the cams thereby be prevented from being reversed. During normal operation of the apparatus, between these limits, the vertical guides 38, bear against the round portions of the cams so that the guiding contact is uniformly and continuously maintained as the bin rises and falls and the cams turn. This action being supplemented by that of cam flanges 15, 16, on sills 37, the vertical alinement of all bin positions is assured.

Having described my invention, I claim:

1. A yielding supported storage bin for pulverized fuel and the like which comprises in combination the bin, a base frame, means for guiding the bin toward and from said base frame along vertical lines, a series of cams journaled on said frame and supporting the bin, connecting mechanism whereby all said cams are compelled to move in unison, and one or more compression springs mounted on the frame and bearing on the under side of certain of the cams.
2. A combination such as set forth in claim 1 in which each spring has a rocking bearing on its coöperating cam.
3. A combination such as set out in claim 1, in which the means for guiding the bin comprise sills for supporting the bin, which sills rest on the cams, and side flanges on the cams engaging the sides of the sills.
4. In an apparatus for yieldingly supporting a superimposed body the combination, with a supporting foundation, of a cam journaled on said foundation about a horizontal axis, a horizontal, flat bearing attached to the supported body and coöperat-

ing with the cam, and spring means tending to rotate the cam in a direction to lift the body, the cam having a flat face on which the above mentioned flat bearing may rest when the body is in a predetermined position.

5. In an apparatus for yieldingly supporting a superimposed body the combination, with a supporting foundation, of a cam journaled on said foundation about a vertical axis, a vertical, flat bearing attached to the supported body and coöperating with the cam, and spring means tending to rotate the cam in a direction to lift the body, the cam having a flat face on which the above mentioned flat bearing may rest when the body is in a predetermined position.

6. In an apparatus for yieldingly supporting and vertically guiding a body the combination, with said body and a supporting foundation, of a plurality of cams journaled in said foundation on parallel horizontal axes and connected together for synchronous motion, and on which cams rest the body to be supported, a flat vertical guide bearing on the supported body resting against a circular surface rotating with each cam, one or more of these bearings being on one side of one cam, and another upon the opposite side of another cam, flanges on the cams engaging vertical surfaces on the supported body which are at right angles to the first above mentioned guide bearings, and means for rocking the cams.

7. The combination, with a movable body and a support limiting the movement of said body in one direction, of a plurality of cams journaled in the support on parallel axes and bearing against the body, means for rotating said cams, and guiding means comprising flanges on the cams perpendicular to the axes thereof engaging opposite sides of the body, and projections from the body having parallel faces at right angles to the cam flanges engaging cylindrical portions of the cams on opposite sides.

WILLIAM O. RENKIN.
